(57) CLAIM

The ornamental design for a magnet game, as shown.

DESCRIPTION

The present invention relates to the features of ornamentation, pattern and shape of a game using magnetic and metallic components. A game apparatus enables a plurality of magnetic components to be places therein, so as to provide unpredictable gaming entertainment. A spherical projectile is rolled from each tossing end with the goal of magnetically attracting said projectile to said magnetic components. The first player to incrementally reach the higher number wins.
